Primary Examiner — John R Yeh

(57) **CLAIM**

The ornamental design for a toddler tower, as shown and described.

DESCRIPTION

FIG. 1 is a perspective view of a toddler tower in a first orientation showing the new design;

FIG. 2 is a top plan view thereof;

FIG. 3 is a bottom plan view thereof;

FIG. 4 is a left-side elevation view thereof;

FIG. 5 is a right-side elevation view thereof;

FIG. 6 is a front elevation view thereof;

FIG. 7 is a back elevation view thereof;

FIG. 8 is a perspective view of the toddler tower in a second orientation with the dowel rod removed;

FIG. 9 is a top plan view thereof;

FIG. 10 is a bottom plan view thereof;

FIG. 11 is a left-side elevation view thereof;

FIG. 12 is a right-side elevation view thereof;

FIG. 13 is a front elevation view thereof;

FIG. 14 is a back elevation view thereof; and,

FIG. 15 is an enlarged view of portion 15 shown in FIG. 1. The equal-length broken lines depict portions of the toddler tower that form no part of the claimed design.

The dash-dot lines in FIG. 1 and FIG. 15 illustrate the boundaries of the enlarged view indicators and form no part of the claimed design.

1 Claim, 15 Drawing Sheets
